VIBRATOR TRANSFORMER AND RECTIFIER

Stephen F. James, Chicago, Ill.

Application April 3, 1933, Serial No. 684,899

19 Claims. (Cl. 171—97)

My invention relates to vibrator transformers and rectifiers and particularly to an arrangement designed for use primarily for supplying plate current for an automobile radio, preferably from the regular starting and ignition battery of the car. It is the object of my invention to provide a new and improved form and arrangement of parts by which an armature member may be given a more positive movement for effecting the desired making and breaking of the primary circuit of the transformer and whereby there shall be an increased effectiveness of such make and break mechanism and a correspondingly increased effectiveness of the transformer action. To this end, it is one of the objects of my invention to provide an arrangement in which oscillation may be suppressed in the primary for cutting down the peaks of the potential at the times when the primary circuit is broken. It is another object of my invention to provide a device of this type in which the vibrator shall operate smoothly and at such high frequency as to prevent a change in the polarity of the armature from that initially set up in the armature. It is one of the objects of my invention to provide an improved construction of this type in which the movement of the armature of the vibrator is effected either principally or entirely by auxiliary fields set up by the use of auxiliary coils mounted either on portions of the core of the transformer or on other core parts in operative relation to the armature. It is one of the objects of my invention to provide an improved arrangement of cooperating coils for producing the operating field within the core of the transformer and for producing an auxiliary field or fields whereby the desired energization of the transformer and the desired movement of the armature may be effected, the arrangement preferably comprising make and break contact mechanism or other switching means controlled by the movement of the armature for making the necessary changes in the circuit connections for bringing about the desired transformer action and concurrent rectification in cases where rectification is desired.

It is one of the objects of my invention to provide an arrangement of this type in which the armature is pivoted at an intermediate point and is given its swinging movement by the joint effect of magnetically operating parts at both ends, the end portions of the armature being formed of magnetic material and having preferably a magnetic connection with each other so that nor-

mally there shall be opposite polarity at opposite ends of the armature, the arrangement preferably being such that the armature may be vibrated at sufficiently high frequency to prevent a change of polarity in the armature from that initially set up therein, the end portions of the armature being adapted normally to stand yieldingly in such position as to insure that the desired initial polarity shall be established in the armature at the start of operation.

It is another object of my invention to improve devices of this type in sundry details hereinafter pointed out. The preferred means by which I have accomplished my several objects are illustrated in the accompanying drawings and are hereinafter specifically described. That which I believe to be new and desire to cover by Letters Patent is set forth in the claims.

In the drawings,—

Fig. 1 is a diagrammatic view of one preferred form of my improved arrangement in which the auxiliary fields for effecting the movements of the armature are produced in the core of the transformer and in which the coils by which such auxiliary fields are produced are connected in series with the coils by which the principal field is produced in the transformer core;

Fig. 2 is a diagrammatic view of another arrangement in which the fields by which the armature is moved are produced in core pieces separate from the core of the transformer;

Fig. 3 is a diagrammatic view of an arrangement similar to that shown in Fig. 2 but involving the use of a double vibrator mechanism which serves to effect both a transformer action and a rectification of the secondary current from the transformer without the use of thermionic valves;

Fig. 4 is a diagrammatic view of an arrangement similar to that shown in Fig. 1 but having the auxiliary coils connected in parallel relation to the primary coils of the transformer;

Fig. 5 is a diagrammatic view of an arrangement similar to that shown in Fig. 1 but having the auxiliary coils connected in a different co-operating relation to the primary coils of the transformer; and

Fig. 6 is a top plan view of the armature and the parts carried thereby as shown in Fig. 1.

Referring now to Fig. 1 of the drawings, 10 indicates a shell type of transformer core having 50 primary coils 11 and 12 mounted upon the central leg of the core and wound in reverse directions with respect to the lead 13 by which said coils are connected to a battery 14. In its upper edge, the core 10 is provided with notches 15 and 15a pro-

viding upwardly projecting arm portions 16 and 17 respectively upon which are mounted coils 18 and 19 respectively.

Upon the upper face of the core 10, I have pivotally mounted an armature 20 formed of magnetic material and arranged to swing toward the arm portions 16 and 17 alternatively. Upon the armature 20, I have provided resilient bars 21 and 21a preferably of brass, forming a support 5 for resilient bars 22 and 22a also preferably formed of brass, bars 23 and 23a being mounted above the bars 22 and 22a, said boss 23 and 23a being preferably formed of commercial tin plate. At opposite end portions of the armature 20, I 10 have provided thin collars 20a of copper about the armature opposite the notches 15 and 15a. The arrangement is such that the bars 21, 22 and 23 and the bars 21a, 22a, and 23a are adapted to vibrate with the armature 20, the 15 device as a whole being balanced so as to permit ready movement of the device in opposite directions. A light spring 24 carried by the armature 20 holds the armature and its connected parts normally in the position as 20 shown in the drawings, the effective strength of the spring 24 being adjustable by the use of a set screw 24a adjustably mounted in a standard 24b.

The brass bars 22 and 22a carry at their ends 30 contact members 25 and 26 respectively preferably of silver, such contacts 25 and 26 being adapted to engage set screws 27 and 28 respectively upon the vibration of the armature 20, such set screws 27 and 28 being adjustably mounted 35 in standards 29 and 30 and being provided with contact portions at their ends formed of tungsten.

In the arrangement shown, the coils 11 and 18 are connected together by a lead 31; the coil 18 is connected with the standard 29 and the set 40 screw 27 by a lead 32; and the bars 22 and 22a are connected with the battery 14 by a lead 33, having a switch 34 interposed therein. At the opposite side, the coil 12 is connected with the coil 19 by a lead 35 and said coil 19 is connected 45 with the standard 30 and the set screw 28 by a lead 36. A by-pass condenser 37 is connected across the switch comprising the contacts 25 and 27 at the left, and a by-pass condenser 38 is connected across the switch comprising the contacts 26 and 28 at the right. The set screws 27 and 28 are further connected by a by-pass condenser 39. In the arrangement shown, the condensers 37 and 38 are of approximately one-tenth of a 50 microfarad capacity each, while the condenser 39 is of approximately one-half of a microfarad capacity.

Upon the central leg of the core 10, I have provided secondary coils 40 and 41 reversely wound with respect to the lead 42 to which said coils are 60 connected. The coils 40 and 41 are further connected by means of leads 43 and 44 with the plates of thermionic valves 45 and 46 respectively. The filaments of the valves 45 and 46 are connected by means of leads 47 with coils 48 and 49 65 respectively wound upon the central leg of the transformer in reverse direction with respect to the common lead 47. A lead 50 connected with the filament circuit 47 is connected with the lead 42 by means of condensers 51 and 52, the lead 42 between the points of connection of the condensers 51 and 52 therewith comprising a choke coil 53, the condensers 51 and 52 and the choke coil 53 constituting an effective filter for smoothing the current through the output leads 42 70 and 50.

With the parts in the condition as shown in Fig. 1, when the switch 34 is closed, a current from the battery 14 is sent through the coil 12 and the coil 19, the arrangement of the parts being such that said coils by the effect of the current therethrough tend to produce the same polarity in the arm portion 17 of the core. The current through the coil 12 at the same time produces the same polarity in the arm portion 16, but the field conditions in the arm 17 are considerably stronger by the influence of the two coils than those in the arm 16 through the influence of the coil 12 alone. The bar 20 is therefore magnetized, producing a pole opposite the arm 17 of reverse polarity as compared with that of the adjacent end of the arm 17 and producing a polarity opposite the arm 16 corresponding to that of the adjacent end of said arm 16. The armature 20 is, therefore, attracted by the strong field in the arm 17 and repulsed by the field in the arm 16, causing the armature to swing in clockwise direction in said Fig. 1 so as to open the circuit at the contact 26 and to close the circuit at the contact 25. In view of the provision of the condenser 38 across the contacts 26 and 28, the polarity of the core 10 as a whole is quickly changed by reason of the reverse induced current through the coil 12, supplemented by the battery current through the coil 11 when the circuit is closed at the contact 25. Such reversed polarity in the arm portion 16 is reinforced by the action of the coil 18 which is connected in cooperative relation with the coil 11. The result is that a strong field is very quickly established in the arm portion 16 serving very 35 effectively to attract the end of the armature 20 at the left, such action being effective before the magnetic field has had time to change in the armature 20. The attraction between the arms 16 and the armature at the left is opposed by a repulsion effect between the arm 17 and the end of the armature at the right, but since the magnetic field is much stronger in the arm 16 than it is in the arm 17, the armature 20 is swung quickly in counter-clockwise direction so as to 40 return the armature to the position as shown in the drawings. The following action is the same as that above described upon the initial stroke of the armature 20, except that upon strokes subsequent to said initial stroke the field conditions in the arm 16 are substantially strengthened by the action of the reverse induced current through the coil 18 due to the breakage of the battery circuit between the contacts 25 and 27 serving more strongly to repel the armature at 45 the left.

It is believed to be unnecessary to describe in detail the effect of the circuit comprising the secondary coils 40 and 41. As will be readily understood, when the field conditions in the core 50 10 as a whole are reversed upon the vibration of the armature 20, secondary induced currents are set up alternately in the coils 40 and 41, which currents flow through the output leads 42 and 55 50 in the same direction so as to be suitable for use in connection with the plates of the tubes of a radio device.

In the operation of the device, the copper collars 20a about the armature 20 serve to short-circuit any current set up in the armature by 60 reason of its oscillating movement in the magnetic fields opposite the arms 16 and 17. Without such control, stray currents would be likely to cause arcing at the axis of the armature or at some other unprotected point so as to cause 65 70 75

damage and ultimately interfere with proper operation of the vibrator unit.

In the arrangement shown in Fig. 2, a core 53a is employed in lieu of the core 10, the central leg of which is provided with coils 11 and 12 as above described and with coils 40 and 41. Coils 54 and 55 are employed in lieu of coils 18 and 19, such coils 54 and 55 being mounted upon pole pieces 56 and 57 respectively formed separately from the core 53a. In the arrangement shown in Fig. 2, the filaments of the valves 45 and 46 are heated by current from a separate battery 58 through leads 58a in lieu of being heated through the medium of secondary coils on the core of the transformer, the output lead 50 being connected with one of said leads 58a. Contact pieces 25a and 26a of tungsten are substituted in lieu of the contacts 25 and 26 of Fig. 1, and the set screws 27a and 28a are provided with contact points of molybdenum in lieu of tungsten as shown in Fig. 1. In the arrangement as shown the copper collars 20a are omitted, but such collars can be used if desired. Bars 21b, 22b and 23b are substituted for the two sets of bars as used in Fig. 1, the contact pieces 25a and 26a being mounted on opposite end portions of the bar 22b.

In the operation of the device as shown in Fig. 2, the armature 20 is actuated entirely by the fields set up in the core parts 56 and 57 independently of the field conditions in the core 53a. When the switch 34 of the arrangement in Fig. 2 is closed, a field is set up in the core part 57 serving to polarize the armature 20 and to move the armature in clockwise direction for opening the circuit at the contacts 26a and 28a and to close the circuit at the contacts 25a and 27a. Upon the opening of the circuit between the contacts 26a and 28a, a reverse induced current through the coil 55 serves quickly to reverse the field in the core part 57 so as to cause a repulsion between the core part 57 and the armature 20. At the same time the battery current through the coil 54 serves to attract the armature at the left, the fields in the core parts 56 and 57 thus cooperating for moving the armature 20 in counter-clockwise direction into the position as shown in said Fig. 2. The frequency of movement of the balanced armature 20 is such that the polarity of the armature 20 remains the same throughout the operation, in contrast to the quickly changing magnetic conditions within the core parts 56 and 57 by the action of the condensers 37 and 38.

I have found in practice that when my invention is used for producing fairly heavy currents, such as are used in connection with neon signs, the tungsten and molybdenum contacts work to better advantage than the silver and tungsten contacts as employed in the Fig. 1 construction. The silver and tungsten contacts are however preferable for producing plate current for radio use.

In the arrangement shown in Fig. 3, the construction is substantially the same as that shown in Fig. 2, except that the valves 45 and 46 are eliminated in Fig. 3 and additional switch means is provided for taking the place of the valves for effecting the desired rectification. In the arrangement shown in Fig. 3, the parts are given the same reference characters as are used in Fig. 2 so far as such parts correspond. In the device of Fig. 3, additional contacts 59 and 60 are mounted upon opposite end portions of the bar 22b, each of such contacts being insulated from the bar 22b by means of blocks 61. Set screws 62 and

63 mounted in standards 64 and 65 respectively are adapted to engage the contacts 59 and 60 alternatively for breaking the circuits through such cooperating contacts in the same timed relation as that of the breaking of the circuits through the contacts 25 and 27 and the contacts 26 and 28.

In the arrangement shown in said Fig. 3, the secondary coil 40 is connected by a lead 66 with the standard 64 and the set screw 62, and the contacts 59 and 60 are connected together by a lead 67 which is extended to serve with the lead 42 as one of the output leads of the transformer. In this device, the armature 20 is provided with short-circuiting collars 20a of copper opposite the ends of the pole-pieces 56 and 57 corresponding to the collars 20a as shown in Fig. 1.

When the switch 34 of the mechanism as shown in Fig. 3 is closed, the armature 20 is vibrated in the same manner as is above described in connection with Fig. 2. The arrangement of the circuits and the contacts is such in said Fig. 3 that when the circuit is complete through the coils 11 and 54 through the medium of the contacts 27a and 25a, the secondary circuit is complete through the coil 40 and the contacts 59 and 62; and such that when the circuit is complete through the primary coil 12 and the coil 55 through the medium of the contacts 28a and 26a the secondary circuit is complete through the coil 41 and the contacts 63 and 60. When the circuit is broken at the left through the primary circuit comprising the coil 11, a high tension secondary current is sent through the coil 40 in one direction. When the circuit through the primary coil 12 is broken, a high tension secondary current is sent through the coil 41 in the opposite direction. Thus a unidirectional flow is established in the output leads 42 and 67 as is desired for use in connection with the plates of a radio. The collars 20a have the same short-circuiting effect as above described in connection with Fig. 1.

The arrangement shown in Fig. 4 is of the same type as that shown in Fig. 1. Coils 68 and 69 are substituted on the arm portions 16 and 17 in lieu of the coils 18 and 19 of said Fig. 1 arrangement. Said coils 18 and 19 are made of a comparatively small number of turns, being connected in series with the primary coils 11 and 12 of the transformer. The coils 68 and 69 of the Fig. 4 construction are formed of a considerably greater number of turns than the number of turns in the coils 11 and 12, and such coils 68 and 69 are connected in parallel with the coils 11 and 12 respectively rather than in series therewith. In the arrangement as shown in Fig. 4, the coils 11 and 12 are connected with the battery 14 by means of a lead 10; the coil 11 is connected with the standard 29 and the contact 27 by a lead 71; the coil 68 is connected between the lead 70 and the lead 71 in parallel with the coil 11 by leads 72 and 73; the coil 12 is connected to the standard 30 and the contact 28 by a lead 74; the coil 69 is connected between the leads 70 and 74 in parallel with the coil 12 by leads 75; and the bars 22 and 22a are connected with the battery 14 by means of a lead 16, such lead 16 comprising a switch 77.

In the device of Fig. 4, the rectification is effected by the use of an auxiliary armature 87 formed of magnetic material and pivotally mounted at an intermediate point therealong at the end of the core 10a opposite to that at which the armature 20 is mounted. Such core 10a is provided with notches 88 and 89 in addition to the notches 15 and 15a, such notches 88 and 89

being located opposite the end portions of the armature 87. Said armature 87 is provided with a plate 90 of magnetic material on its upper face adjacent to the notch 89, serving to bring the right-hand end of the armature including said plate 90 into somewhat closer relation to the core 10a than that of the left-hand end of the armature in the position of the parts as shown in said Fig. 4. Collars 91 of thin sheet copper are secured about the end portions of the armature 87 opposite the notches 88 and 89. Bars 92, 93 and 94 corresponding to the bars 21b, 22b and 23b of the arrangement as shown in Fig. 2 are provided, the bar 93 being provided with contact pieces 95 and 96 at its end portions adapted to engage set screws 97 and 98 adjustably mounted in standards 99 and 100 respectively. In the arrangement shown in said Fig. 4, the armature 87 is held at the limit of its movement in clockwise direction by a light spring 101 engaging a set screw 102 adjustably mounted in a standard 103. The parts are so arranged that the armature and its connected parts are substantially balanced with respect to the axis about which the armature is adapted to swing.

In this arrangement of Fig. 4, the standard 99 and the set screw 97 are electrically connected with the secondary coil 40 by a lead 104; the standard 100 and the set screw 98 are electrically connected with the secondary coil 41 by a lead 105; and leads 106 and 107 are connected respectively with the bar 93 and the coils 40 and 41, said leads 106 and 107 serving as the output leads for the high tension induced current impulses.

When the switch 77 of the Fig. 4 construction is closed, coils 12 and 69 are connected in parallel with each other with respect to the battery through the contacts 28 and 26, while coils 11 and 68 are connected in series with each other, with the coil 11 in transformer relationship to the coil 12. The coil 69 is connected so as to reinforce the field produced in the arm portion 17 by the coil 12. At the same time an induced current through the coil 11 acting through the medium of the coil 16 opposes the field in the arm portion 16 as set up by said coil 12. The field set up by the cooperating forces in the arm portion 17 is stronger than the field set up by the opposing forces in the arm portion 16, with the result that the armature 20 is polarized and is swung in clockwise direction in said Fig. 4. At the same time, a field is set up in the core 10a at the notches 88 and 89 and of the same polarity at both of said notches. This field in the core 10a sets up a field in the armature 87 whereby the armature is moved in counter-clockwise direction in said Fig. 4 by reason of the fact that the coupling is closer opposite the notch 89 than it is opposite the notch 88. As the armature 87 starts to swing in counter-clockwise direction, the influence of the field at the right is increased and the influence of the field at the left is decreased, with the result that by the time the circuit is broken between the contacts 96 and 98 at the right and a new contact is effected between the parts 95 and 97 at the left the magnetic field is fully established in the armature 87 with opposite polarity at its end portions. This movement of the armature 87 takes place at precisely the same instant as that at which the movement of the armature 20 occurs in clockwise direction as above described.

Upon the opening of the circuit between the contacts 26 and 28 due to the clockwise movement of the armature 20, the reverse induced current

impulse through the coil 12 and the battery current through the coil 11, brought about by the closing of the primary circuit at the contacts 25 and 27, produces a changed polarity in the core 10a and in the core arms 16 and 17, serving to swing the polarized armature 20 in counter-clockwise direction again to the position as shown in said Fig. 4. At the same time, such changed polarity in the core 10a serves to repulse the armature 87 at the right opposite the notch 89 and to attract said armature 87 at the left opposite the notch 88 for swinging such armature 87 back to the position as shown in said Fig. 4, such reaction upon the armature 87 being dependent upon the easy and quick change of the magnetic conditions in the core 10a and the comparatively much slower change in the magnetic conditions in the armature, this result being attained or at least greatly facilitated by the provision of the condensers 37, 38 and 39 in the battery circuits.

With the armatures 20 and 87 oscillating in unison but at all times in opposite directions, the circuits through the secondary coils 40 and 41 are alternately made and broken at precisely the same time that the circuits through the primary coils 11 and 12 respectively are made and broken. The result is that the induced current impulses pass in one direction through the secondary coil 40 and in the opposite direction through the secondary coil 41, all of such impulses passing in the same direction through the output leads 106 and 107.

By the use of an auxiliary armature 87 as shown in Fig. 4, with the contacts for the secondary circuits on the auxiliary armature, as contrasted with the arrangement shown in Fig. 3, in which the contacts for both the primary and the secondary circuits are all on a single armature 20, I have provided for a more easy and a more certain adjustment of the parts to the desired working condition. In the arrangement shown in Fig. 4, the action of the auxiliary armature 87 is tuned with respect to a separate spring 101 from that effective in connection with the armature 20, giving a certain leeway with respect to the adjustment which is not attained in the use of the construction of Fig. 3. Moreover, by the use of the two armatures, the pressure between the contacts is distributed to better advantage for obtaining the desired results.

In the arrangement shown in Fig. 5, the construction is similar to that shown in Fig. 4 except for the connection of the cooperating parts and the omission of the rectifying means. In the arrangement shown in said Fig. 5, the coil 11 is connected by a lead 78 with the standard 29 and contact 27; the bar 22 is connected with the battery 14 by a lead 79 including a switch 80; the battery 14 is connected with the coil 11 in turn by a lead 81. The coil 12 is connected by means of a lead 82 with the standard 30 and the contact 28. The coil 68 upon the arm portion 16 is connected at one end by a lead 83 to the battery lead 79 and is connected at its opposite end by a lead 84 with the standard 30 and contact 28. The coil 69 upon the arm portion 17 is connected at one end by a lead 85 to the battery lead 79 and is connected at its opposite end by a lead 86 to the standard 29 and contact 27.

In the arrangement as shown in said Fig. 5, when the switch 80 is closed, the coil 12 is connected with the battery 14 through the lead 82, the contacts 28 and 26 and the lead 79. Under such circumstances the coil 68 is thrown out of effective operation since it is substantially short-

circuited by the metallic connection through the contacts 28 and 26. At the same time, the coil 11 and the coil 69 are connected through the leads 78, 86, 85, 79 and 81 with each other and with the battery 14. Inasmuch as the coil 69 has a very considerable number of turns, substantially all of the battery current will pass through the circuit comprising the coil 12 which is of very much lower resistance. The two principal forces effective under such circumstances are the primary current through the coil 12 and the induced current through the coils 11 and 69, the coil 69 being connected in such relation that the induced current therethrough causes it to cooperate with the coil 12 in the establishment of strong magnetic field conditions in the arm portion 17. Under such circumstances, the armature 20 is polarized and is moved in clockwise direction in said Fig. 5, serving to open the circuit between the contacts 26 and 28 and to close the circuit between the contacts 25 and 27. Upon the breaking of the circuit between the contacts 26 and 28, the reverse induced current through the coil 12 very quickly changes the direction of the flux in the core 10. When the circuit is closed between the contacts 25 and 27, the coil 69 is in effect short-circuited, and the coils 12 and 68 by the effect of the induced current therein serve to reenforce the effect of the battery current in the coil 11 for the establishment of a strong magnetic field in the arm portion 16. The result is that the armature 20 is quickly moved in counter-clockwise direction again to the position as shown in said Fig. 5, this result being effected so quickly that the polarity of the armature 20 is not changed.

In the operation of the device as shown in Fig. 5, the battery current through one of the primary coils 11 and 12 in opposition to the induced current through said primary coil serves to suppress oscillation so as to cut down the peaks of the current when the primary circuit is broken at the contacts. The result is that I have attained a smoother and more even current which is more fully serviceable for radio purposes.

I have found in practice in connection with devices of the several types shown in the drawings that satisfactory results are attained by the use of primary coils 11 and 12 of about 60 or 70 turns each; that coils 18, 19, 54 and 55 produce satisfactory results when provided with 12 to 20 turns each; and that satisfactory results are attained by the provision of 1500 to 2000 turns in each of the coils 68 and 69. In practice, I have attained satisfactory results by the provision of a straight bar armature made of silicon steel. Inasmuch as the armature in each instance is designed to retain its initial polarity, and since means is provided for insuring that this polarity shall be the same for succeeding periods of operation, it will be appreciated that each of the armatures may be in the form of a permanent magnet if such arrangement is desired.

While I prefer to employ the arrangement as shown in my drawings and as above described, it is to be understood that my invention is not to be limited thereto except so far as the claims may be so limited by the prior art.

I claim:—

1. In a mechanism of the type described, the combination of an armature member having end pieces of magnetic material which are magnetically connected to each other, magnetic core parts adjacent to said end pieces toward which said end pieces are movable, and means for produc-

ing changing magnetic field conditions involving changing polarity in said core parts adjacent to the end pieces of the armature for causing said armature to move alternately toward said core parts, said field producing means comprising coils on said core parts respectively, circuit means for connecting said coils with a source of electrical energy, and switch means controlled by the movements of the armature for producing the required changes in said circuit connections for causing said armature to be magnetically actuated successively in opposite directions, the arrangement being such that said end pieces of the armature have the same polarity throughout the operation of the device for insuring effective attraction and repulsion alternatively between the end pieces and the core parts.

2. In a mechanism of the type described, the combination of an armature member pivotally mounted at an intermediate point and having end pieces of magnetic material at opposite ends, magnetic core parts adjacent to said end pieces toward which said armature is adapted to swing alternatively, yielding means adapted normally to hold said armature swung to the limit of its movement toward one of said core parts, and means for producing changing magnetic field conditions involving changing polarity in said core parts adjacent to the end pieces of said armature for causing said armature to swing alternately toward said core parts in such rapid succession as to prevent a change in the polarity of the end pieces of said armature from that set up by the initial magnetization thereof, said field producing means comprising coils on said core parts respectively, circuit means for connecting said coils with a source of electrical energy, and switch means controlled by the swinging movement of said armature for producing the required changes in said circuit connections for causing said armature to be magnetically actuated successively in opposite directions.

3. In a mechanism of the type described, the combination of an armature member pivotally mounted at an intermediate point and having pole pieces of magnetic material at opposite ends magnetically connected together for obtaining normally opposite polarity at the ends of the armature, magnetic core parts adjacent to said pole pieces of the armature toward which said armature is adapted to swing alternatively, yielding means adapted normally to hold said armature swung to the limit of its movement toward one of said core parts, coils on said core parts respectively, and circuit means for feeding electrical energy alternately to said coils for causing said armature to vibrate and comprising switch means controlled by the movement of the armature for producing the required changes in said circuit means for bringing about the vibratory movement of the armature.

4. In a mechanism of the type described, the combination of an armature member pivotally mounted at an intermediate point and having end pieces of magnetic material at opposite ends, magnetic core parts adjacent to said end pieces toward which said armature is adapted to swing alternatively, yielding means adapted normally to hold said armature swung to the limit of its movement toward one of said core parts, two coils on said core parts respectively, two other coils, circuit means connecting said second named two coils with said first named two coils respectively for feeding electrical energy alternately to said coils for causing said armature to vibrate

- and comprising switch means controlled by the movement of the armature for producing the required changes in said circuit means for bringing about the vibratory movement of the armature, two other coils in transformer relationship to said second named two coils respectively, and circuit means connecting said third named two coils for permitting the flow of secondary currents by induction therethrough.
5. In a mechanism of the type described, the combination of an armature member pivotally mounted at an intermediate point and having end pieces of magnetic material at opposite ends, magnetic core parts adjacent to said end pieces 15 toward which said armature is adapted to swing alternatively, yielding means adapted normally to hold said armature swung to the limit of its movement toward one of said core parts, contact pieces carried by said armature at its opposite 20 end portions, other contact members mounted in position to engage said first named contact pieces alternatively as said armature is swung between the limits of its movements, coils on said core parts respectively, and circuit means connected 25 with said contacts and with said coils for feeding electrical energy alternately to said coils and arranged whereby the magnetic fields set up successively in said core parts serve by magnetic action to swing said armature alternately in opposite directions.
6. In a mechanism of the type described, the combination of an armature member pivotally mounted at an intermediate point and having pole pieces of magnetic material at opposite ends magnetically connected together for obtaining normally opposite polarity at the ends of the armature, magnetic core parts adjacent to said pole pieces of the armature toward which said armature is adapted to swing alternatively, yielding 35 means adapted normally to hold said armature swung to the limit of its movement toward one of said core parts, two coils on said core parts respectively, two other coils, circuit means connecting said second named two coils with said first named two coils respectively for feeding 40 electrical energy alternately to said coils for causing said armature to vibrate and comprising switch means controlled by the movement of the armature for producing the required changes in said circuit means for bringing about the vibratory movement of the armature, two other coils in transformer relationship to said second named two coils respectively, and circuit means connecting said third named two coils for permitting the flow of secondary currents by induction therethrough.
5. In a mechanism of the type described, the combination of a shell type of core having a portion at one side at one end within which the density of the field is considerably increased as compared with the remainder of the core when the normal magnetic field is set up in said core, coil means for producing an effective field in said core, an armature mounted at the end of said core and having a pole piece of magnetic material movable alternatively toward and from the core by magnetic action for effectively cutting down the resistance to the flux at said point of increased density, an auxiliary coil mounted on said core adjacent to said portion of increased density tending when energized to produce a magnetic flux in said core adjacent to the coil independently of said first named coil means, and means for feeding current to said coils comprising switch means controlled by the swinging movements of

the armature whereby said coils by their cooperation produce a high frequency vibration of said armature.

8. In a mechanism of the type described, the combination of a shell type of core having a notch in its outer face at one end portion providing an outwardly directed arm portion, coil means for producing an effective field in said core as a whole, an armature having a pole piece of magnetic material movable yieldingly toward and from the core by magnetic action, a coil mounted on said outwardly directed arm portion of the core tending when energized to produce a magnetic flux in said outwardly directed arm portion independently of said first named coil means, and means for feeding current to the several coils comprising switch means controlled by the swinging movement of the armature whereby said coils by their cooperation produce a high frequency vibration of said armature.

9. In a mechanism of the type described, the combination of a shell type of core having a notch at each side of the core in its outer face at one end portion providing an outwardly directed arm portion at each point, coil means for producing an effective field in said core as a whole, an armature member having end pieces of magnetic material which are magnetically connected to each other and which are located adjacent to said arm portions and are yieldingly movable toward and from the arm portions opposite said notches for decreasing the resistance to the flux across the notches, coils mounted on said arm portions respectively tending when energized to produce a magnetic flux in the arm portion independently of said first named coil means, and means for feeding current to the several coils comprising switch means controlled by the movements of the armature whereby said coils by their cooperation produce a vibration of said armature of such high frequency as to prevent a change in the polarity of the armature from that initially established therein.

10. In a mechanism of the type described, the combination of a core, a coil on said core, an armature comprising an end piece of magnetic material movable yieldingly toward and from said core, means for feeding electrical energy intermittently to said coil for magnetizing the core and causing the armature to move toward and from the core, and circuit means of non-magnetic material about said armature providing a closed circuit for the currents induced in the armature by reason of its movement through the magnetic field of said core.

11. In a mechanism of the type described, the combination of a core, coils on said core, an armature pivotally mounted at an intermediate point therealong so as to swing toward and from the core, bars mounted on said armature at opposite side portions thereof and extending in opposite directions therealong, contact pieces carried by said bars respectively adjacent to the ends of said armature, other contact members in position to be engaged alternatively by said contact pieces as said armature oscillates between the limits of its movement, and means for feeding electrical energy alternately to said coils through the alternately engaging contacts.

12. In a mechanism of the type described, the combination of a core, coil means on said core, an armature pivotally mounted adjacent to said core so as to swing yieldingly toward the core, a resilient bar mounted on said armature adja-

- cent to the pivotal axis of the armature, a second resilient bar mounted on said first named bar but extending toward the end of the armature beyond the end of the first named bar, a flexible bar mounted on said second resilient bar and extending toward the end of the armature but terminating short of the end of said second bar, a contact piece carried by said second resilient bar at a point beyond the ends of the other two bars, a contact member in position to be engaged by said contact piece when said second bar swings with said armature to the limit of its movement away from the core, and means for feeding electrical energy to said coil 5 means through said contact parts whereby an intermittent magnetic field in said core serves to swing the armature toward the core for breaking the engagement between said contact parts.
13. In a mechanism of the type described, the combination of a core, coil means on said core, two armatures pivotally mounted adjacent to said core so as to swing yieldingly toward the core, switch means controlled by the movement of one of said armatures, means for feeding current to said coil means through said switch means whereby an intermittent magnetic field is set up in said core for swinging both of said armatures toward the core at intervals and serving to open the circuit through said switch means, secondary coil means on said core in transformer relationship to said first named coil means, other switch means controlled by the movement of the other one of said armatures, and means comprising connections between said secondary coil means and said other switch means whereby a unidirectional current is fed through said connections.
14. In a mechanism of the type described, the combination of a shell type of core, two primary coils on the central leg of said core, two armatures adjacent to said core at opposite ends of the core respectively and each pivotally mounted at an intermediate point therealong so as to swing toward and from the core, means for holding each of said armatures yieldingly at the limit of its motion in one direction, notches in the core opposite the end portions of each of said armatures, switch means controlled by the movement of one of said armatures, means for feeding current to said primary coils alternately through said switch means whereby a magnetic flux is set up in said core in alternately opposite directions serving to swing both of said armatures toward the core at intervals against the action of said yielding means, secondary coil's on said core in transformer relationship to said first named coils, other switch means controlled by the movement of the other one of said armatures, and means comprising connections between said secondary coils and said other switch means whereby said secondary coils are connected alternately in circuit for the flow of induced currents therethrough and whereby the induced current impulses through both of said coils flow in the same direction through a portion of said circuit connections.
15. In a mechanism of the type described, the combination of an armature member having end pieces of magnetic material which are magnetically connected to each other, magnetic core parts adjacent to said end pieces toward which said end pieces are yieldingly movable, coils on said core parts for producing changing magnetic field conditions involving changing polarity in said core parts adjacent to the end pieces of the
- armature for causing said armature to move alternately toward said core parts, secondary coils in transformer relation to said first named coils on said core parts, and means for feeding current to said first named coils and for connecting said secondary coils in closed circuits in such arrangement as to cause said armature to move alternately toward said core parts at such high frequency as to prevent the end pieces of the armature from changing polarity from that first established therein, and comprising switch means for the primary circuits and other switch means for the secondary circuits controlled by the movements of the armature for producing the required changes in the primary circuit connections for causing said armature to be magnetically actuated successively in opposite directions and the required changes in the secondary circuit connections for insuring that the induced currents from said secondary coils shall flow in the same direction through the output leads of the secondary circuit means.
16. In a mechanism of the type described, the combination of a shell type of core having a notch at each side of the core in its outer face at one end portion providing an outwardly directed arm portion at each point, coil means for producing an effective field in said core as a whole, an armature member pivotally mounted at an intermediate point and having end pieces of magnetic material at opposite ends opposite said notches and magnetically connected to each other, with each of said end pieces in position to decrease the resistance to the flux across one of said notches when the armature swings toward that notch, yielding means adapted normally to hold said armature swung to the limit of its movement toward one of said arm portions, coils mounted on said arm portions respectively each tending when energized to produce a magnetic flux in the arm portion independently of said first named coil means, means for feeding current to the several coils comprising switch means controlled by the movement of the armature whereby said coils by their cooperation produce a vibration of said armature, condenser means connected across the switch means at each end of the armature, secondary coils in transformer relationship to said first named coils, and means for connecting said secondary coils in closed circuits and comprising switch means controlled by the movement of the armature and operating for shifting the connections in said secondary circuits in such manner as to insure that the induced currents from said secondary coils flow in the same direction through the output leads of said secondary circuit means.
17. In a mechanism of the type described, the combination of a core, a coil on said core, an armature comprising an end piece of magnetic material movable yieldingly toward and from said core, and means for feeding electrical energy intermittently to said coil for magnetizing the core and causing the armature to move toward and from the core, said feeding means comprising a switch in the form of a contact piece of tungsten cooperating with a contact formed of molybdenum, with one of said contact parts movable with the armature for making and breaking the circuit.
18. In a mechanism of the type described, the combination of a core bar, coil means on said core bar, core means providing an all-metal return path for the flux threading said coil means, other return path means connecting the end por-

tions of said core bar and providing greatly increased resistance to magnetic flux at one point as compared with the principal remaining portions, an armature member comprising a pole piece of magnetic metal movable toward and from said second named return path means at said point of increased resistance serving as an auxiliary core part for bridging said portion of increased resistance, circuit means comprising 5 switch means operated by said armature member serving to connect said coil means periodically with a source of electrical energy for establishing a flux at intervals in said core for moving said pole piece by magnetic attraction periodically 10 toward the core, and other coil means adjacent to a magnetic metal portion of said armature member connected by said circuit and switch means alternatively with a source of electrical energy serving after each movement of said 15 pole piece toward said core means to move the armature member by magnetic attraction in the opposite direction for carrying said pole piece away from the core.

19. In a mechanism of the type described, the 25 combination of a core bar, two coils on said core bar, core means providing an all-metal return path for the flux threading said coils, other

return path means connecting the end portions of said core bar and providing greatly increased resistance to magnetic flux at one point as compared with the principal remaining portions, an armature member comprising a pole piece of 5 magnetic metal movable toward and from said second named return path means at said point of increased resistance serving as an auxiliary core part for bridging said portion of increased resistance, circuit means comprising switch means 10 operated by said armature member serving to connect said two coils alternatively with a source of electrical energy for establishing a flux alternately in opposite directions in said core serving with the flux in one direction to move said 15 pole piece by magnetic attraction toward the core, and other coil means adjacent to a magnetic metal portion of said armature member connected by said circuit and switch means with a source of electrical energy for energization concurrently with one of said first named coils serving after each movement of said pole piece toward 20 said core means to move the armature member by magnetic attraction in the opposite direction for carrying said pole piece away from the core. 25

STEPHEN F. JAMES.
